US0D1011409S

(12) **United States Design Patent** (10) **Patent No.:** **US D1,011,409 S**
(45) **Date of Patent:** **** Jan. 16, 2024**

(54) **EYEGLASSES**

(71) Applicant: **Oakley, Inc.**, Foothill Ranch, CA (US)

(72) Inventors: **Joon H. Kim**, Hacienda Heights, CA (US); **Nicolas Adolfo Garfias**, Long Beach, CA (US)

(73) Assignee: **Oakley, Inc.**, Foothill Ranch, CA (US)

(**) Term: **15 Years**

(21) Appl. No.: **29/792,943**

(22) Filed: **May 2, 2022**

(51) LOC (14) Cl. **16-06**

(52) U.S. Cl. **USPC D16/325**

(58) **Field of Classification Search**

USPC D16/300, 315, 318, 325, 326; D24/110.1, 110.2, 110.3; D29/102, 104, D29/105, 106, 107, 108, 109, 110

CPC G02C 1/02; G02C 1/04; G02C 2200/08; G02C 1/00; G02C 7/16

(57) **CLAIM**

The ornamental design for eyeglasses, as shown and described.

DESCRIPTION

FIG. 1 is a top front perspective view of eyeglasses showing the claimed design;

FIG. 2 is a front elevation view thereof;

FIG. 3 is a rear elevation view thereof;

FIG. 4 is a right side elevation view thereof, the left side elevation view being a mirror image thereof;

FIG. 5 is a top plan view thereof; and,

FIG. 6 is a bottom plan view thereof.

The broken lines in the figures show portions of the eyeglasses that form no part of the claimed design.

1 Claim, 6 Drawing Sheets
